UNITED STATES PATENT OFFICE

FREDERIC M. CARD, OF BRIDGEPORT, CONNECTICUT, ASSIGNOR TO THE SINGER MANUFACTURING COMPANY, OF ELIZABETH, NEW JERSEY, A CORPORATION OF NEW JERSEY

SEWING MACHINE WORK-SUPPORT

Original application filed May 28, 1930, Serial No. 456,380. Divided and this application filed July 16, 1931. Serial No. 551,113.

This invention relates to improvements in sewing machine work-supports and has for its primary object to provide, in a simple manner, work-supporting means which will minimize distortion of the work resulting from the anchoring of the seam-forming stitches, and which will also serve to assist in the control of the thread-chain when chaining-off between successively stitched articles. A further object of the invention is to provide an improved fabric-margin supporting device in a sewing machine adapted to join abutted or slightly overlapping fabric-margins.

The foregoing and other objects and advantages in view, together with means whereby the same may be carried into effect, will best be understood from the following description of a preferred embodiment of the invention illustrated in the accompanying drawing, in which:

Fig. 1 is a top plan view, partly in section, of the work-support, presser-foot and trimming mechanism of a sewing machine containing a preferred embodiment of the invention. Fig. 2 is a sectional view of the work-supporting and feeding means, together with a side elevation, partly in section, of the presser-foot. Fig. 3 is a top plan view of the throat-plate and of the improved fabric-margin supporting member applied thereto. Fig. 4 is a top plan view of the presser-foot shoes.

As described in my prior patent application Serial No. 456,380, filed May 28, 1930, of which this application is a division, the invention is illustrated as embodied in a sewing machine having a work-supporting post 1, upon the upper end of which a throat-plate 2 is secured by the screws 3. The throat-plate has a plurality of feed-slots 4 and 4' for feed-dogs 5 and 6, and a transverse needle-slot 7 for a vertically reciprocatory and laterally vibratory needle 8. The rear wall of the needle-slot is partly cut away to

provide a generally V-shaped thread-clearance recess or depression 9 in the upper face of the throat-plate, which depression is inclined downwardly toward the needle-slot 7 from its pointed end remote from said 50 needle-slot.

Disposed in spaced relation above said recess 9 is a chaining-off finger 10, extending across the needle-slot 7 and having its upper surface preferably substantially flush with 55 the upper face of the throat-plate, the under side of said finger being inclined upwardly toward its pointed free end terminating rearwardly of the path of the needle 8. The chaining-off finger 10 is preferably formed 60 integral with a ridged fabric-margin supporting member 11, whose crest 12 is disposed centrally of and parallel with the line of seam formation and terminates in advance of the needle-slot 7 in a downwardly inclined 65 surface 13 merging into the upper face of the chaining-off finger. The member 11 is removably disposed in a recess 14 formed in the upper face of the throat-plate in front of the needle-slot and between the adjacent front 70 feed-slots 4 and 4', said member being secured to the throat-plate by screws 15.

The feed-dog 5 operates through the feed-slots 4, and the feed-dog 6 through the feed-slot 4' and the front end of the feed-slot 4 75 adjacent to said slot 4', as will be more clearly understood from a more complete disclosure of the feeding mechanism in my before mentioned prior patent application Serial No. 456,380. The feed-dogs are preferably 80 capable of differential work-advancing movements, whereby the margin of a body material at one side of the margin-supporting member 11 may, if desired, be advanced faster than the margin of the body material 85 disposed at the opposite side of said member.

Yieldingly opposed to the feed-dogs is a presser-foot including adjacent foot-plates or shoes 16 and 17 preferably capable of yielding vertically independently of each 90

other and of a chain-controlling or auxiliary foot 18 disposed between the heels of the foot-plates 16, 17 and directly rearwardly of the needle-path. The foot-plates 16 and 17 are spaced from each other beginning from the upturned toes thereof to provide a fabric-margin receiving slot 19 which terminates at a point directly in front of the needle-path, at which point the adjacent edges of the foot-plates curve inwardly into abutting relation, whereby the fabric margins are directed downwardly underneath the presser-foot. The presser-foot is preferably so disposed with respect to the throat-plate that the crest 12 of the fabric-margin supporting member rises substantially centrally of the presser-foot slot 19.

The fabric-margins upturned in the presser-foot slot 19 are preferably trimmed by a mechanism including a horizontally disposed ledger-blade 20 and a horizontally vibratory cutting blade 21, of which the latter may be vibrated by any suitable mechanism. The trimmer-blades are disposed in recessed 25 guard-blocks 22 and 23 secured upon the foot-plates 16 and 17, said guard-blocks together providing a diverting surface 24 for initially deflecting the trimmed-off margins away from the needle-path and to a diverter-blade 30 25 which completes the deflection of said trimmed-off margins. The diverter-blade is so supported that it may be swung into and out of operative position, being illustrated in its throw-out position in Fig. 1 of the drawings.

It will be understood from the foregoing description that in the present machine the fabric-margins, which are upturned in the slot 19 between the presser-foot plates 16, 17, 40 are supported by the ridged member 11 as said margins are advanced by the feed-dogs 5 and 6 to trimming position. After being trimmed, the body-material margins are directed downwardly by the presser-foot 45 along the inclined surface 13 of said member into abutting or slightly overlapping relationship upon the wider portion or base of the chaining-off finger 10, where the laterally vibrating needle alternately penetrates the adjacent fabric-margins and in 50 cooperation with any suitable loop-taker mechanism unites said adjacent margins by zigzag stitches. Inasmuch as the stitches embrace the finger 10, which constitutes a 55 continuation of the crested or ridged member 11, there is a minimum of tendency to distort the fabric-margins by the setting of the stitches, which latter are free to slide off the tapered finger 10 by the provision of the 60 throat-plate depression 9 below said finger. The present construction furthermore provides for chaining-off, the thread-chain being controlled by the auxiliary foot 18 and a section of the feed-dog 4 opposed thereto. 65 By providing the member 11 with the chain-

ing-off finger and by detachably securing said member upon the throat-plate, the process of manufacture is materially simplified and the cost of construction and replacement is materially reduced.

Having thus set forth the nature of the invention, what I claim herein is:—

1. In a sewing machine, in combination, stitch-forming mechanism including a reciprocatory needle, feeding mechanism, a throat-plate, presser means opposed to the throat-plate having spaced work-engaging toes between which upturned margins of material are adapted to pass toward the stitching point, a ridged fabric-margin supporting member having a crest which extends lengthwise and substantially centrally of the line of seam within the space between said toes and terminates in a chaining-off finger, and means for detachably securing 85 said fabric-margin supporting member upon the throat-plate with its crest above the upper surface of the throat-plate and its chaining-off finger projecting rearwardly beyond the path of the needle. 90

2. In a sewing machine, in combination, stitch-forming mechanism including a reciprocatory needle, feeding mechanism, a throat-plate having a needle-slot elongated crosswise of the line of seam formation and its rearward wall partly cut away to provide a recess in the upper face of the throat-plate inclined downwardly toward said needle-slot, presser means opposed to the throat-plate having spaced work-engaging toes between which upturned margins of material are adapted to pass toward the stitching point, a ridged fabric-margin supporting member having a crest which extends lengthwise and substantially centrally of the line 105 of seam within the space between said toes, the crest of said member being beveled downwardly in advance of the needle to merge into the upper surface of a chaining-off finger integral with said member, and means for detachably securing the fabric-margin supporting member upon the throat-plate with its chaining-off finger overlying said throat-plate recess in spaced relation thereto. 110

In testimony whereof I have signed my name to this specification.

FREDERIC M. CARD.
